Ferguson, III et al.

(10) **Patent No.:** **US D627,527 S**
(45) **Date of Patent:** **** Nov. 16, 2010**

(54) **PET BED HEATING PAD**

(75) Inventors: **Ben T. Ferguson, III**, Knoxville, TN (US); **Marc E. Brush**, Knoxville, TN (US); **Jason R. Graves**, Knoxville, TN (US); **Nianhong Zhou**, Tianhe District (CN)

(73) Assignee: **Radio Systems Corporation**, Knoxville, TN (US)

(**) Term: **14 Years**

(21) Appl. No.: **29/320,910**

(22) Filed: **Jul. 8, 2008**

(51) **LOC (9) Cl.** **30-99**

(52) **U.S. Cl.** **D30/199**

(57) **CLAIM**

We claim the ornamental design for a pet bed heating pad, as shown and described.

DESCRIPTION

FIG. 1 is a perspective view of the design of the present invention for a pet bed heating pad;

FIG. 2 is a top view thereof;

FIG. 3 is a bottom view thereof;

FIG. 4 is a rear view thereof;

FIG. 5 is a front view thereof;

FIG. 6 is a right view thereof; and,

FIG. 7 is a left view thereof.

The broken line elements are not claimed.
